UNITED STATES PATENT OFFICE

127,479

DESIGN FOR A COLOGNE BOTTLE OR SIMILAR ARTICLE

John D. Buckingham, Chicago, Ill., assignor to Lucien Lelong, Inc., Chicago, Ill., a corporation of Illinois

Application December 4, 1940, Serial No. 97,060

Term of patent 3½ years

To all whom it may concern:

Be it known that I, John D. Buckingham, a citizen of the United States and a resident of the city of Chicago, in the county of Cook and State of Illinois, have invented a new, original, and ornamental Design for a Cologne Bottle or Similar Article, of which the following is a specification, reference being had to the accompanying drawing, forming a part thereof.

On the drawing:

Figure 1 is a top plan view of the cologne bottle or similar article, showing my new design, and

I claim:

The ornamental design for a cologne bottle or similar article, as shown.

JOHN D. BUCKINGHAM.
